Fig. 5.

Fig. 7.

FIGS. 1 and 2 are side views taken from opposite sides of a bicycle wheel reflector showing our new design;

FIGS. 3 and 4 are end views of the bicycle wheel reflector taken respectively from the left and right of FIG. 1;

FIGS. 5 and 6 are views taken respectively from the bottom and top of FIG. 1; and

FIG. 7 is a perspective view of the bicycle wheel reflector on a reduced scale, the wheel and clip being shown in broken lines for illustrative purposes only.

We claim:

The ornamental design for a bicycle wheel reflector, substantially as shown and described.
